Inventor

Emanuel Geaard

UNITED STATES PATENT OFFICE.

EMANUEL GUANO, OF CHELSEA, NEW JERSEY.

APPARATUS FOR DRYING ALIMENTARY PASTE.

1,168,722.

Specification of Letters Patent. Patented Jan. 18, 1916.

Application filed May 29, 1914. Serial No. 841,788.

To all whom it may concern:

Be it known that I, EMANUEL GUANO, a citizen of the United States, residing at Chelsea, in the county of Atlantic and State 5 of New Jersey, have invented certain new and useful Improvements in Apparatus for Drying Alimentary Paste, of which the following is a specification.

This invention relates to apparatus for 10 drying alimentary pastes, such as macaroni, spaghetti, noodles and the like, in which the goods are suspended and given a motion in the drying chamber.

The object of my invention is to provide 15 a machine or apparatus for suitably supporting pendant strips or stems of alimentary paste and giving the material a uniform movement in the drying chamber, so that it shall be evenly subjected to the drying 20 medium, such as warm dry air, at the proper temperature for effecting the drying operation without causing bending or twisting of the goods.

The movement imparted to the strips or 25 stems of paste will expedite the drying operation, so that it may be effected in a few hours and the temperature and atmosphere in the drying chamber will be so controlled that the material will dry in straight regular form.

The matter constituting my invention will be defined in the claims.

I will now describe the details of construction and arrangement of my machine by 35 reference to the accompanying drawings in which:

Figure 1 represents a sectional elevation of the casing and revolute frame. Fig. 2 represents a sectional elevation on a plane 40 at right angles to that shown in Fig. 1. Fig. 40 at right angles to that shown in Fig. 1. Fig. 3 represents a horizontal section through the upper part of the casing with parts in top plan view. Fig. 4 represents a sectional detail on enlarged scale showing one of the 45 detail on enlarged scale showing one of the sleeve shafts of the revolute frame. Fig. 5 represents a sectional detail view of one 5 of the pivoted frame connections. Figs. 6 and 7 represent respectively a fragmentary side view and an end view of a supporting 50 rod or cane in the pivoted supporting frame. Fig. 8 represents part of a rod or cane supporting stems or rods of macaroni.

I provide a chamber or casing (1) of metal or other suitable material and hinge 55 thereto at one side doors (2) which may form one of the side walls. At the top may

connect an inlet pipe (3) having a valve (a) for admitting dry warm air. A branch pipe (4) having a valve (b) may connect with pipe 3 for admitting cooler or warmer air as may be required to produce the desired temperature and the most effective atmosphere in the drying chamber. Approximately in the central part of the chamber is mounted a revolute drying frame (5) supported at opposite ends on short stud 60 shafts (7) in journal boxes or bearings (6) having stuffing boxes (6^a) or other suitable means for making a tight joint as shown in Fig. 4. For the revolute frame I provide at each end a short sleeve shaft (8) having a flange (9) which may be cast therewith. To this flange are bolted the end frame arms or bars (10) and (11) substantially at right angles one to the other, as 70 shown in Fig. 2. I have shown but two cross bars 10 and 11, but evidently a greater number may be used if desired. To the stub shafts 7 are secured sprocket wheels (12) by means of screws 7^a on opposite 75 sides of the casing. On top of the casing, or in any suitable position, a transverse shaft (14) is supported in journal boxes (15) and is provided near each end with a small sprocket wheel (13), secured thereto 80 by screws. A sprocket chain (16) is passed over the wheels 12 and 13 at each end of the frame on opposite sides of the casing. To shaft 14 is connected a fast and a loose 85 belt pulley (17 and 17^a). The short shafts 90 7 will be inserted into the sleeve shafts 8 and may be engaged by keys, or the sleeves may have angular openings, as square and the shafts 7 be of the same shape. The short 95 shafts 7 may be readily removable, so that the sleeve shafts 8, carrying the frame 5, may be detached from the stub shafts 7 and the frame removed from the casing for 100 charging or loading with stems or tubes, or strips of fresh macaroni as it comes from the press, or for removing the dried material.

In order to remove the stub-shafts 7 from the sleeve shafts 8 the sprocket wheels 12 may be first removed from the stub-shafts 105 by taking out the screws from the flanges of said wheels, or the sprocket chains 16 may be removed from either the wheels 12 or 13, and the shafts 7 can then be drawn out so that their inner ends shall rest simply in the bearings 6, 6^a. It will be evident 110 that the frame 5, carrying the pivoted frames

20, can then be removed from the casing through the side having the doors 2, 2.

Pivoted supporting frames (20) are connected to the outer ends of the cross bars 10 5 and 11. These frames are composed of angular end frame bars (21—22) in the shape of an inverted V, and their outer ends are connected by bottom cross bars (25) shown on enlarged scale in Figs. 6 and 7. The 10 short middle part 22 of each frame is pivotally connected to the outer end of an arm 10 or 11 by a pivot bolt (18), Fig. 5, having a plain smooth part 19 and a screw threaded part which is screwed into a 15 threaded opening in the arm 10. The part 22 of the frame engages with the part 19 of the bolt and is separated from the arm 10 by washers (23). A split pin (24) may be passed through a hole in the bolt 18. The 20 bottom cross bar (25) Figs. 6 and 7, is made with a series of notches (26) and is transversely curved and riveted to the bars 21. A series of rods or canes (28) having annular grooves (29) and end heads (30) 25 are placed at their grooved portions in the notches 26. This construction and connection of the rods 28, and bars 25, hold the end frames together and prevent the possibility of a rod and its load of macaroni 30 dropping out of place in the frame. Each rod can also be readily lifted out of place and replaced with a load of macaroni strips or stems. Brace or tie rods 27 and 27^a connect the end frames 21 for strengthening the 35 construction. In the bottom is provided openings (35) for the escape of heavy damp air and any water of condensation that may form on the walls.

As the macaroni paste comes from the 40 press in strips or tubes, and cut the desired length, it is folded in the middle over the rods 28 as shown at (d) Fig. 8, and the rods when loaded are placed in the notches 26 of the frame bars 25 till a frame is filled. 45 All of the pivoted frames 20 are thus filled and the main frame 5 may then be inclosed in the casing 1, and engaged with the short shafts 7. The doors 2 will then be closed and warm dry air admitted through pipe 50 (3). The power shaft (14) is then revolved, imparting motion to frame (5). By the slow revolving motion given to the frame the air is forced up the pendant macaroni tubes and all around them so as to 55 uniformly dry them without danger of causing them to bend or twist. On the contrary the tubes or stems are dried and kept straight in the desired condition for packing. After the drying operation has been completed the frame (5) may be removed 60 from the casing and unloaded and then recharged and returned to the casing for another drying operation, and so on repeatedly.

If desired the frame or reel (5) may be left in the chamber and the rods (28) filled 65 with macaroni and placed in the frames (20) or removed therefrom as required.

The whole operation is very simple and convenient and can be quickly carried out. By doing away with a central shaft through 70 the drying chamber there is no obstruction to the pendant strips or tubes of macaroni as the frame revolves; and further, the frame (5) may be readily removed and replaced and engaged with the short shafts 75 (7). Modifications may be made in the details of construction without departing from the spirit and scope of my invention. Other material than macaroni or spaghetti may be placed in the pivoted frames (20) 80 for drying and the material may be differently arranged or disposed therein.

Having described my invention, what I claim, and desire to secure by Letters Patent is:—

1. In a drier, the combination with a casing, of a removable, revoluble frame or reel mounted therein on short stub shafts having 85 means for turning them.

2. In a drier, the combination with a 90 casing, of a removable, revoluble frame or reel mounted at each end on a short detachable shaft, supporting or carrier frames for goods pivotally connected to the main frame, and operating gearing.

3. In a drier, the combination with a casing, of a removable revoluble frame having short sleeve shafts at each end, short detachable stub shafts adapted to engage with said sleeve shafts, supporting frames 100 for goods pivotally connected to the main frame and operating mechanism.

4. In a drier, the combination with a revoluble frame, of a goods supporting frame or carrier pivotally connected to said frame 105 and having notched cross bars, and having detachable supporting rods provided with annular grooves and end-heads, said rods resting at their grooved portions in the notches, for supporting macaroni in pendant position.

5. In a drier, the combination with a casing, of a removable revoluble frame or reel mounted therein on short stub shafts, and goods supporting frames pivotally connected 115 to said revoluble frame and each having a series of detachable rods for supporting macaroni strips or stems in pendant position.

In testimony whereof I affix my signature in presence of two witnesses.

EMANUEL GUANO.
